Almoni Clark's Coffe Mill
Letters Patent

The Schedule referred to in these Letters Patent contains a specification of the same containing a description in the words of the said Almoni Clark himself of his improvement in the Coffe Mill.

It is known that Almoni Clark of Boston in the County of Suffolk and State of Massachusetts has invented a new and useful improvement in machinery for grinding coffee and other substances, and that the following is an exact description of the same as invented or improved by me. The mill thus improved may consist of five pieces. First. The back part which is composed of the back shell, one half of the hopper, the plate, the end and one half of the spout. Secondly. The back grinder which is moveable and of a concave concave form of iron riveted to the back shell and resting with its concave side on the convex side of the back shell. Thirdly. A concave-convex roller with grinding teeth, in both sides, having an angle with bearing at both ends, with a flange on the periphery, and a divided as hereinafter specified. Fourthly. The front grinder of a concave-convex form, from which extends the front half of the hopper, spout, and end. Fifthly. The circular segment which is to form a bed on one side, and a plate on the other with an eye by which it is secured or otherwise attached to the back. Considering the back shell is concave on one side, and convex on the other, with a circular plate, on the outer side to admit the upper end, of the back grinder, and the ground corn of the same, to a depth nearly of the thickness of the flange, segment, on the convex within the outer circle of the shell. The circular flange of the back shell is not angry, on the upper side, sufficient to admit the back half of the hopper, the lower part whereof projects on the concave surface of the shell below the circular flange, a competent length, to prevent the mill from beginning to grind, from passing between the grinder and shell. The back grinder, should be riveted as the second piece has been and may consist of the concave side of the circular plate touching upon and riveted to the convex side of the circular plate touching the ground roller, and the upper part of the flange of the back shell.

part of the hopper without said the top thereof to save the parts together, and in the form the circular flite can be continued through the hopper without said the circular segment, as in the mill herein first described: or, the part of the circular flite of the hopper ground passing through the hopper, and equal in size to the circular segment, may be made separate from the grinder, and mounted thereto, being drawn to the circular segment, or this said part of the circular flite, and the circular segment may be made and made a whole circular piece, so that in either case the segments of the flange, will pass through a continuous circular flite, or the mill may be cast, as to be applied to a board with a hopper of tin or any suitable material. The preceding specification describes an improvement of the small mill, for grinding coffee, for which I have already obtained a Patent. The pieces, comprising this small mill, and improvement, are of cast iron, but may be made of any other suitable material.

Claim herein as my invention or improvement the following things, namely to wit, the carrying of the circular flite, and the grinder, through or across the hopper and the application of a mill for grinding coffee and whole instances of the flange on the same, separated into segments at convenient distances from each other as hereinbefore described. Dated at Berlin, Africa, the 17th day of June 1853.
